UNITED STATES PATENT OFFICE.

THOMAS E. SHULL, OF LEWISTOWN, PENNSYLVANIA.

METHOD OF SETTING UP TENPINS.

Specification of Letters Patent No. 8,614, dated December 23, 1851.

To all whom it may concern:

Be it known that I, THOMAS E. SHULL, of Lewistown, in the county of Mifflin and State of Pennsylvania, have made certain new and useful improvements in constructing tenpin-alleys and also an improved mode of adjusting or setting up the pins, by which a player can practice the game without the aid of boys or assistants to set up the pins 10 and return the balls; and I do hereby declare that the following is a full, clear, and exact description of the construction and operation of the same, reference being had to the annexed drawings, making a part of this 15 specification, in which—

Figure 1, is a side elevation. Fig. 2, is a back view in elevation. Fig. 3, is a plan or bird's-eye view of the alley.

Similar letters of reference indicate corresponding parts in each of the several figures.

The nature of my invention consists 1st in having the alley inclined so that the terminus will be elevated somewhat above the 25 end at which the player is stationed, the terminus is of semicircular shape so that the balls in striking against it are turned round and pass down to the player on either side of the alley owing to the inclination, grooves 30 being made for the balls to run in.

My invention consists 2d in having a cord attached to each pin the several ends passing up through an adjusting screen and also guide screens and attached to a circular 35 disk or plate, to this plate is attached a cord which passes over suitable pulleys and winds round a wheel near the player, by turning the wheel the pins are raised or lowered and properly adjusted in the alley, with aid of 40 the adjusting and guide screens as will be hereafter described.

To enable others skilled in the art to make and use my invention I will proceed to describe its construction and operation.

45 A, Figs. 1, 2 and 3, is the alley. B, is the semicircular terminus which projects upward somewhat above the alley as seen in Figs. 1 and 2; in Fig. 3, the semicircular shape of the terminus is seen, the inclination of the 50 alley is seen in Fig. 1. (a) (a) (a) (a) Fig. 3, are the grooves at the sides of the alley for the balls to run in when passing down to the player. The alley A, should be sufficiently inclined so as to allow the balls 55 to pass down to the player, say an inclination of about one inch to ten feet. The end of

the alley where the player is stationed is sunk a suitable distance so as to require as little bending or stooping as possible in taking the balls from the grooves, this recess or sunken space is indicated by C Figs. 1 and 3. Now it will be seen that when a ball is cast at the pins and strikes the semicircular terminus B, the ball will react or turn and pass down one of the grooves (a) till stopped by the projection or cleft (b) which is at the extreme end of the alley, see Fig. 3 and dotted lines in Fig. 1. The cushions ordinarily used in alleys which cover the terminus are not needed with the semicircular terminus, 60 the cushion has a tendency to destroy the force of the ball and that is requisite in ordinary alleys as they are taken up by boys at the end of the alley where the pins are placed and rolled down to the player in inclined gutters, but in my case the reaction or perhaps more properly a certain amount of the original force of the ball is required in order that it may have sufficient momentum, favored by the inclination of the alley 65 to pass down one of the grooves to the player, after being turned by the terminus.

D are the pins. These pins are turned with shoulders (e) on them, see Figs. 1 and 2, the portion from the shoulder to the top 70 being of uniform thickness.

E is an adjusting screen placed at a suitable height directly over the pins, or directly over the spot on the alley that the pins occupy when properly adjusted.

The screen is secured between two uprights F, F, Fig. 2. Holes (d) are bored through the screen to receive the upper portion of the pins, see dotted lines in Figs. 1 and 2. These holes are placed the proper 90 distance apart and correspond precisely to the position of the pins on the alley. When properly adjusted, the dotted lines in Fig. 3 show the shape of the adjusting screen and the pins D (which are properly adjusted on the alley) correspond to the holes through the screens.

(e) are cords attached to the tops the pins D, one cord to each pin, these cords pass up through the holes (d) in the adjusting 105 screen and also through the holes (f) and (g) in the guide plates or screens G, H, placed over the adjusting screen F, and at suitable distances apart see Figs. 1 and 2, the plates or screens G, H, are secured between the same uprights E, F, as the adjusting screen E, the ends of the cords (e)

are attached to a circular disk or plate I. The guide screens are for the purpose of keeping the cords (e) in a proper direction for instance the holes (f) in the guide screen 5 G, correspond to and are directly over the holes (d) in the adjusting screen E, and the holes (g) in the guide screen H, are directly under the eyes (m) which are attached to the under surface of the circular plate or 10 disk I, the cords being attached to the eyes; by this means the cords (e) have a proper direction and the pins are raised by the cords so that the tops of the pins will enter or pass into the holes (d) these screens G, H, 15 being necessary as the cords (e) are attached to the circular plate or disk I, within a smaller compass than the pins occupy on the alley when set upon the holes in the adjusting screen E. On the upper surface of 20 the disk or plate I there is an eye (h) through which passes a horizontal rod or bar J. The ends of this rod or bar work between guides (i) (i) and the uprights F, F. The guides are represented by dotted lines 25 in Fig. 2, in Fig. 1. One end of the rod or bar J, is seen between the guide (i) and upright F. K is a cord attached to the eye (h) and passing up over the pulley (j) which is attached to the cross piece L, of 30 the uprights F, F. The cord K, then passes over the pulley (k) which is attached to a cross piece M, on two uprights N, N, one only of which is seen in Fig. 1, the cross-piece M, and pulley (k) being shown by 35 dotted lines, the cord then passes down and over a wheel O, which is on a shaft (l) the bearings of the shaft being in the uprights N, N. A crank P, is on one end of the shaft (l) as seen in Figs. 1, and 2. The crank P 40 is designed to be placed within reach of the player, and upon turning the wheel O, in the proper direction the pins D, as will readily be seen are elevated and brought up to the adjusting screen E the tops of the pins

passing through the holes (d) in the screen 45 E till the shoulders (c) of the pins bear against the under surface of the screen see Fig. 2. While in this position the pins have the same relative position that they have when properly adjusted on the board, owing 50 to the holes (d) in the screen as has been before stated all that is required to be done now is to let the pins gently down by reversing the motion of the wheel O till they reach the alley turning the wheel O, sufficiently to 55 allow a suitable play or "slack" to the cores (e) so that the pins may be knocked over by the balls.

The rod or bar J, the ends of which work between the guides (i) (i) and uprights 60 F, F is for the purpose of keeping the circular disk or plate I working in a vertical direction when the pins are raised or lowered.

Thus it will be seen that persons may practice the game of tenpins without the aid of an assistant to adjust the pins or to throw back the balls, the pins can also be adjusted in the alley in less time than an assistant can do it and in a more perfect and precise manner.

Having thus described the nature and operation of my invention what I claim as new and desire to secure by Letters Patent is—

Attaching the pins D, to a disk or plate I, by means of cords (e) in combination 75 with the adjusting screen E, and guide screens G, H, by which the pins are properly adjusted or set up on the alley A upon raising and lowering the disk or plate I as described, the disk or plate being operated by 80 means of the cord K passing over the pulleys (j) (k) and around the wheel O power being communicated to the shaft (l), or by other mechanical means.

THOS. E. SHULL.
